(57) **CLAIM**

The ornamental design of a handle for upright vacuum cleaner, as shown and described.

DESCRIPTION

FIG. 1 is a perspective view of a handle for upright vacuum cleaner showing our new design;

FIG. 2 is a perspective view thereof, with the handle isolated;

FIG. 3 is a front elevational view thereof;

FIG. 4 is a left side elevational view, the right side being a mirror image thereof;

FIG. 5 is a rear elevational view thereof; and,

FIG. 6 is a top plan view thereof.

The details shown in broken lines in FIGS. 1 and 5 are for illustrative purposes only and form no part of the claimed design.
